UNITED STATES PATENT OFFICE.

MAURICE LACHMAN, OF NEW YORK, N. Y., ASSIGNOR, BY MESNE ASSIGNMENTS, TO BETHLEHEM STEEL COMPANY, OF BETHLEHEM, PENNSYLVANIA, A CORPORATION OF PENNSYLVANIA.

METAL WHEEL.

1,396,443.

Specification of Letters Patent.

Patented Nov. 8, 1921.

Application filed March 14, 1919. Serial No. 282,591.

To all whom it may concern:

Be it known that I, MAURICE LACHMAN, a citizen of the United States, and a resident of New York, in the county of New York and State of New York, have invented certain new and useful Improvements in Metal Wheels, of which the following is a specification.

My invention relates to that class of wheels in which a metal plate or disk is employed for the web or spoke part of the wheel, said disk or plate having hub or rim portions for the wheel integral with it.

The object of my invention is to secure cheapness and ease of construction together with superior strength.

My invention aims primarily at a construction of disk or plate suitable for use with wheels in which a separate rim or felly 20 part attached or secured to the edge of the disk is employed.

To these ends my invention consists essentially of a sheet metal disk or plate comprising web or spoke and hub part integral 25 with one another and a rim part also integral therewith but bent over to form transverse supporting brackets supporting the separate rim or felly as hereinafter more particularly described.

30 The invention further consists in so bending or forming the ears constituting said brackets that they will have a bearing against the face or side of the disk to thereby afford a stronger support for the rim.

35 In the accompanying drawings:

Figure 1 is a side elevation of a disk and attached rim constructed in accordance with my invention.

40 Fig. 2 is a transverse section on the line 2—2 Fig. 1.

Fig. 3 illustrates a preferred construction of the disk in which the web or spoke part is furnished with integral tongues operating as struts or braces and further shows a modification in the manner of forming the integral supporting brackets of the rim.

Fig. 4 is a transverse section on the line 4—4 Fig. 3.

50 Fig. 5 is a plan of the preferred form of metal blank in which the brackets and tongues are formed.

Fig. 6 shows in transverse section one of the ways in which a multiplicity of disks may be employed to form a wheel; Fig. 7 an-

other modification in the disposition of a pair of disks forming the component parts of the same wheel.

1 indicates a metal plate or disk constituting the web or spoke portion of the wheel and perforated at its center 3 for the axle 60 or attachment of the strengthening hub or bearings. 5 indicates a separate metal rim or felly and 6 indicates supporting brackets upon which said rim is supported and to which it is attached by spot welding or by other means. Said brackets 6 in the blank as shown in Fig. 5 are formed integrally with the plate 1 at the edge thereof and in order that they may have a firm support to sustain the rim they are bent at two lines, 70 one, line 7 by which they are turned down to a plane transverse to the plane of the disk to afford a bearing for the inner surface of the rim, and the other the line 8 at right angles to the first, whereby, at a free edge 75 9, said bracket is given a bearing against the face of the disk. The lines of cut in the blank as clearly shown in the Fig. 5 are the radial lines 10 and the detached lines 11 transverse to the lines 10 which permit the 80 ears to be bent on the lines 8 as already described.

If desired one extreme outer corner of the ear may be curved as indicated at 13 thereby avoiding the presence of any sharp 85 exposed corner in the face of the finished wheel or disk. In addition to the brackets thus provided for the rim, tongues 14 may be cut out of the web or spoke part between the circumferentially continuous hub part 90 of the disk and edge and bent to one side of the plane of the disk for attachment to the flange of the enlarged portion 15 of the hub as shown in Fig. 4, thereby strengthening the finished wheel against side strains or torsional effects while the wheel is in operation. 95 As will be understood in the art the main body portion of the disk may be slightly concaved so that it will be better adapted to cushion the wheel against road shocks.

100 Instead of forming the supporting brackets in the manner already described, they may be formed as indicated in Fig. 4 to support the rim and to have a bearing on the face of the disk. In this instance the ears 105 formed by the radial slits at the edge of the disk are bent outwardly as at 18 to afford the flat bearing 20 for the inside of the rim

and at 19 are furnished with a reverse bend to bring the outer edge of the ear into a position to engage the face of the disk.

As shown in the various Figs. 1 to 4 inclusive the supporting brackets formed from the bent ears may extend alternately in opposite directions from the plane of the disk toward the edge of the rim 5, in which instance the plane of the disk would be approximately central of the general plane of the wheel or at a point substantially midway between the edges of the rim.

Obviously the wheel may be made up from a single disk with rim attached thereto as described or a number of disks may be assembled to form the wheel. Thus, as indicated in Fig. 6, a pair of disks may be arranged beside one another with the ears projecting from their contiguous faces towards one another and the ears of one disk extending into spaces between the ears or brackets of the other, while the brackets on the outer faces of the disks extend out to approximately the edge of the rim.

While I have so far described the brackets as extending in opposite directions from the plane of the disk, they might all extend in the same direction and a pair of the disks be used to form the wheel and afford a support across approximately the whole width of the rim. This modification is illustrated in Fig. 7. In this case the two disks may be furnished at the opening 3 with inturned flanges 17 which engage one another and space the disks apart at the center. Other modifications in the disposition or use of the disks with their supporting brackets to make up a wheel will readily occur to those skilled in the art.

Obviously the rim and disk may be secured together in any desired way as for instance by spot welding the rim to the brackets. Likewise, if desired, the brackets may be welded to the face of the disk at the places where they engage the same.

What I claim as my invention is:—

1. In a wheel of the character described, a sheet metal plate constituting the spoke part of the wheel and slit radially at its circumferential edge to provide supporting brackets bent to extend alternately in opposite directions transversely to the plane of the wheel integral therewith and engag-

ing the inner surface of the rim, said brackets having also a bearing against the face 55 of the plate.

2. In a wheel of the character described, a metal disk constituting the spoke part of the wheel and having at its edge rim supporting brackets cut from but integral with 60 the disk and bent to have a bearing against the face of the disk.

3. In a wheel of the character described, a metal disk constituting the spoke part of the wheel and having its entire edge cut and 65 bent to form supporting brackets for the rim over the whole interior circumference thereof, said brackets having also a bearing against the face of the disk.

4. In a wheel of the character described, 70 a metal disk constituting the spoke part of the wheel and having an edge cut and bent to form supporting brackets for the rim, said brackets having a bearing by their edges against the face of the disk.

5. In a metal wheel of the character described, the combination with a metal rim, of a multiplicity of metal disks each having its entire circumferential edge cut radially and bent transversely to afford supports for 80 the rim.

6. In a metal wheel of the character described, the combination with a metal rim, of a metal disk having ears cut in the circumferential edge thereof and bent on two 85 lines as described to engage and form a support on the inner face of the rim for the inside of the rim and to engage or have a bearing by an edge against the face of the disk.

7. In a wheel of the character described, a metal disk having its edge formed into brackets integral with said disk by two bends at right angles to one another, one to provide a bearing for the inner side of the 95 rim and the other to form a bearing of an edge of the bracket against the face of the disk.

Signed at New York in the county of New York and State of New York this 12th 100 day of March A. D. 1919.

MAURICE LACHMAN.
